UNITED STATES PATENT OFFICE.

HUGH PARTRIDGE, OF ORTEGA, FLORIDA, ASSIGNOR, BY DIRECT AND MESNE ASSIGNMENTS, TO JAMES H. PAYNE, OF JACKSONVILLE, FLORIDA.

SPRINKLER.

1,180,526.

Specification of Letters Patent. Patented Apr. 25, 1916.

Application filed December 8, 1915. Serial No. 65,756.

To all whom it may concern:

Be it known that I, HUGH PARTRIDGE, a citizen of the United States, residing at Ortega, in the county of Duval and State of Florida, have invented a new and useful 5 Sprinkler, of which the following is a specification.

The present invention appertains to 10 sprinklers such as are used for watering grass, plants or other vegetation, and it is the object of the invention to provide a 15 rotary sprinkler of novel and improved construction.

It is the object of the invention to 20 provide a sprinkler which will have a relatively slow speed of rotation due to the arrangement of the outlet apertures, whereby the water will be projected in a more effective manner than ordinarily, to cover a larger area, and to distribute the water evenly 25 akin to that of rain.

It is also within the scope of the invention to provide a sprinkler having the characteristics above noted, and which is comparatively 30 simple and inexpensive in construction and manufacture, as well as being practical and efficient in use.

With the foregoing and other objects in view which will appear as the description 35 proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:—

Figure 1 is a plan view of the sprinkler. Fig. 2 is a central vertical section thereof.

In carrying out the invention, there is provided a horizontal discharge pipe 1 constructed of brass or other suitable material, and having its ends closed by plugs 2. A sleeve 3 of suitable metal is cast or fitted upon the central portion of the pipe 1, to act as a weight for counteracting the thrust 45 created by the pressure of the water, said sleeve being of any suitable weight. The sleeve 3 and central portion of the pipe 1 are provided with a lower threaded aperture 4 threadedly receiving the upper end

of a vertical tubular member 5 for delivering the water into the pipe 1.

The tubular member 5 is mounted for rotation within the upper reduced portion 6 of a vertical coupling 7 adapted to be threaded or otherwise secured over the end 60 of a pipe, hose or the like. The coupling 7 can be constructed of aluminum or other suitable metal, and the ends of the reduced portion 6 are provided with counter bores 9 in which bushings 8 are fitted, the tubular 65 member 5 being journaled in said bushings 8. The space between the bushings 8 can be filled with lubricant, for lubricating the contacting portions of the member 5 and bushings, so as to reduce friction and wear. 70 Collars or nuts 10 are engaged upon the lower end of the member 5 to coöperate with the lower bushing 8 for holding the member 5 in place.

A salient feature of the invention resides 75 in the peculiar arrangement of the outlet apertures or orifices 11 in the pipe 1, each arm of said pipe having a helical series of apertures 11. The inner apertures of the two series are arranged adjacent the sleeve 80 3 and are disposed at the top or crest of the pipe 1 so as to discharge the water vertically. The apertures of one arm extend from the top to one side of said arm adjacent the free end of said arm, so that the outer aperture 11' discharges the water horizontally or tangentially relative to the path of rotation, while the intermediate apertures of said arm discharge the water at various angles above the horizontal plane of rotation. The apertures of the other arm extend along a helical line of greater pitch than the helical line along which the apertures of the first mentioned arm extend, whereby the outer aperture 11'' of the second mentioned 85 arm directs the water upwardly at an angle above the horizontal plane of rotation, while the intermediate apertures of the second mentioned arm direct the water at a greater angle upwardly. It will be observed that 90 the apertures are disposed at one side of the vertical plane in which the axis of the pipe 1 is arranged, the other side of the pipe being imperforate, so that the water is discharged to one side of the pipe 1 from either 95 arm thereof. However, since the apertures of one arm extend downwardly closer to the horizontal plane of rotation, the reaction of

the water discharged from the respective apertures will be slightly greater than the reaction of the water discharged from the apertures of the other arm, whereby the pipe 5 or head 1 will rotate slowly in one direction. The water discharged from one arm tends to retard or impede the rotation of the pipe 1, while the reaction resulting from the discharge of the water from the other arm 10 overcomes said retarding reaction and thus propels or drives the pipe at a relatively slow speed in the horizontal plane of rotation.

The present sprinkler is adapted for use 15 in overhead irrigation, the sprinklers being attached at suitable intervals to water pipes extended over the ground to be irrigated, although the sprinkler may be used for watering lawns, or the like. The sprinkler 20 can be inexpensively manufactured so that the sprinklers can be provided at suitable distances over an entire farm, without entailing prohibitive expense. With an ordinary sprinkler, the water is discharged from 25 each arm in the same direction relative to the direction of rotation whereby the water is delivered to the vegetation at the same angle, whereas with the present device, the water is delivered from one arm at one 30 angle to the vegetation, and is delivered at the opposite angle from the opposite arm, which results in the even distribution and watering of the plants akin to that of rain. The water will thus be sprayed to all sides 35 of the plants, while with ordinary sprinklers it is generally the case that the plants are left dry upon one side. Due to the fact that the reaction of the discharged water at the opposite arms tends to counteract one another, the water is discharged a greater distance from the pipe, so that a greater area 40 will be watered than with the use of an ordinary sprinkler, it being understood that the water can be discharged farther from a stationary or slowly revolving member, than 45 from a member which rotates faster due to the reaction of the water, since the faster the

member is rotated by the reaction of the water, the less will the water be thrown from the said member. The arrangement of the 50 apertures is therefore of advantage in several respects, viz., it provides for the relatively slow speed of rotation of the pipe or head, it facilitates the projection of the water from the pipe, it increases the area 55 covered by the water even with a lower pressure, and it results in the water being evenly distributed akin to that of rain. The apertures nearest the center of the pipe throw the water upwardly so that it will fall 60 around the sprinkler, and the farther away from the center of the pipe the apertures are, the farther will the water be thrown from the sprinkler, to assure the uniform watering of the area at the center of which 65 the sprinkler is arranged.

Having thus described the invention, what is claimed as new is:

A sprinkler embodying a horizontal pipe having its ends closed, a vertical pipe having its upper end attached to the central portion of the horizontal pipe and mounted for rotation about a vertical axis, the horizontal pipe having opposite arms and said arms each having a series of apertures extending along a helical line, the inner apertures being at the top of the pipe and one helical line being of greater pitch than the other so that the outer aperture of one series is disposed at one side of the respective arm 70 to discharge the water approximately horizontally while the outer aperture of the other series discharges the water upwardly at an angle, the intermediate apertures all discharging the water upwardly at an angle 75 to the same side of the pipe.

In testimony that I claim the foregoing as my own, I have hereto affixed my signature in the presence of two witnesses.

HUGH PARTRIDGE.
